CIGARETTE BOX OR CIGARETTE BOX
HOLDER

Carlos Agustín Spiking, Buenos Aires, Argentina

Application May 1, 1934, Serial No. 723,315

6 Claims. (Cl. 206—41)

The present invention refers to a cigarette-box or a cigarette-box holder and other convenient articles and has for its object to facilitate the taking out of the cigarettes in such a manner as will render this operation an easy one and prevent the cigarettes from being damaged either by the fingernails, or otherwise, when handled by their owner or the individual they are being offered to.

10 The box or protecting case forming the object of this invention is characterized in that it may slide along the cigarette-package, thus allowing of the cigarettes to be readily taken out since it offers them with their ends freely exposed. As 15 soon as a cigarette or cigarettes have been taken out, the case embodying the invention automatically covers the remaining cigarettes again.

In order that the invention may be fully understood and readily put into practice, it is by 20 way of example shown in the attached drawing wherein:

Figure 1 is a lateral elevation of the box or case in its normal position;

Figure 2 is a perspective view of the same, in 25 opened and compressed position;

Figure 3 is a cross section through line A—B of Fig. 1;

Figure 4 shows the box or case while in expanded, i. e., totally extended position;

30 Figure 5 is a perspective view showing the case in a semi-mounted state, and

Figure 6 is a plan view similar to that shown in Fig. 5.

In the various figures of the drawing, equal 35 visible parts are indicated by equal reference numerals and/or letters.

In accordance with the attached drawing, the device consists of two strips 1 and 2, of paper having a strong texture, as for instance, thin 40 cardboard or of metal or other flexible material. These strips are in mutual relationship as regards the position they occupy in the cigarette-package 3, strip 1 being placed longitudinally, and strip 2 transversally.

45 Referring, in the first place, to strip 1, this is bent at its two ends, thus forming the edges "a" and "a'". Two portions of both ends are, in turn, bent to the inside so as to form the two interior surfaces "b" and "b'" as well as the two exterior surfaces "c" and "c'", due to the said folds being juxtaposed against the front sides of the package 3, as will be seen from Fig. 5, when a central band is furnished for the base of the said package to adhere to.

50 Strip 2 is slipped between the two surfaces "b"

and "c" and thereby forms the transversal sheath, with the central portion thereof being lodged within this cavity; its two ends "f" and "f'" are then made to pass through the cavity formed by the surfaces "b'" and "c'", when the surfaces will be interlaced, as may be gathered from Fig. 3, the portions "g" and "g'" of the said strip 2 covering the sides of the cigarette-package 3.

It will be noted also that the edges "a" and "a'" prevent the strip 2 from slipping off by itself longitudinally of the package 3 since it is hooked up on the said edges.

The operation of the device is as follows:

The surfaces "c" and "c'" act as elastic members when the case is compressed and the cross strip 2 is caused to slide downwardly so as to leave the upper portion open, with the ends of the cigarettes freely exposed (Fig. 2), for in the preceding paragraphs we have seen just what connection there is between the two strips 1 and 2, such connection being determined by the fact that the second strip is lodged within the folds of the first one. The sliding action is thus brought about by simple manipulation. When 20 the package is released it will become covered again, owing to the tendency of the surfaces "c" and "c'" to return to their normal position.

It will be further noted that the surfaces "b" and "b'" of the sheath will be shorter than the surfaces 30 "c" and "c'" when the case is formed, whereby a difference in length is provided as will be seen from Figs. 1 and 5, the object of the same consisting in limiting the sliding action referred to.

This box or case may be used by itself for accommodating cigarettes within the same, or it may be utilized as a receptacle for cigarettes already contained in any known class of cigarette-packages, in which latter case it would be sufficient for the package to be attached by any known 40 means at its base to the central portion 2 of strip 1, to bring about the same effect. In the first mentioned case, a lid or covering consisting of any kind of strip or wrapping would have to be applied to the box so as to prevent the cigarettes from being sold open at the tobacconist's, such lid being adapted to be torn off by the consumer when he wants to extract a cigarette in the manner just described.

If an ordinary cigarette-package duly introduced in the box or box-holder of my invention were used, the consumer, as has been said, would simply tear off the lid whereupon he will be at liberty to take out a cigarette during the operation of the holder.

For example, for better practical application of this invention, the strips 1 and 2 may be made in only one piece or divided into two or more portions, or joined together with or without adhesive.

It is obvious that certain other detail and construction modifications may be introduced without thereby departing from the scope of my present invention which is clearly determined in and by the appended claims.

What I claim is:

1. A protecting case or box-holder for holding a package of cigarettes or a group of loose cigarettes, comprising a slideable sheath enveloping the upper portion of the sides of said package while terminating short of the lower end thereof, and an outer strip extending beneath said package and extending upward exteriorly upon two opposite sides of said package and said sheath to form upwardly extending flexible side members, which are retained at the upper edges of said two opposite sides of said sheath in order to retain said outer strip in assembled relation with said sheath and allow compression of the case with consequent outward expansion of said flexible side members and lowering of the sheath upon the package so as to expose the upper end thereof above said sheath, the sheath being returned by straightening of the flexible side members so as again to cover the sides of the upper end of the package upon releasing the case from compression.

2. A protecting case according to claim 1, wherein the upwardly extending flexible side members are retained by the upper edges of the two opposite sides of the sheath by being folded inwardly over said upper edges and extending downwardly with said two opposite sides of the sheath and terminating within said sides.

3. A protecting case according to claim 1, wherein the upwardly extending flexible side members are retained by the upper edges of the two opposite sides of the sheath by being folded inwardly over said upper edges and extending downwardly with said two opposite sides of the sheath and terminating at the lower edges of the latter in the form of retaining flaps bent outwardly under said lower edges and upwardly between the sides of said sheath and the exterior portions of the strip forming the flexible side members.

4. A protecting case according to claim 1, wherein the upwardly extending flexible side members are retained by the upper edges of the two opposite sides of the sheath by being folded inwardly over said upper edges and extending downwardly with said two opposite sides of the sheath and terminating within said sides, and wherein the sheath consists of a transversely disposed strip passing upon one side of the case within one of said retaining flaps between one of the upwardly extending flexible side members and the portion thereof folded over the corresponding upper edge of said case and extending down within the same, which strip is bent about the side edges of said folded down portion and bent inwardly about the side edges of the correspondingly opposite folded down portion of the other upwardly extending flexible member and having the two ends thereof terminating within the space between said other upwardly extending flexible member and its folded down portion.

5. A protecting case according to claim 1, wherein the upwardly extending flexible side members are retained by the upper edges of the two opposite sides of the sheath by being folded inwardly over said upper edges and extending downwardly with said two opposite sides of the sheath and terminating within said sides, and wherein the sheath consists of a transversely disposed strip passing upon one side of the case within one of the upwardly extending flexible side members and the portion thereof folded over the corresponding upper edge of said case and extending down within the same, which strip is bent about the side edges of said folded down portion and bent inwardly about the side edges of the correspondingly opposite folded down portion of the other upwardly extending flexible member and having the two ends thereof extending within the other opposite flap and terminating within the space between said other upwardly extending flexible member and its folded down portion.

6. A protecting case according to claim 1, wherein the sheath has the form of a rectangular tube while the outer strip is U-shaped and assembled with the sheath solely at the upper extremities of the resulting U.
